UNITED STATES PATENT OFFICE.

YSABELLA D. McDONALD, OF LOS ANGELES, CALIFORNIA.

AUXILIARY AIR INLET AND MIXING DEVICE FOR MOTOR VEHICLES.

Application filed July 19, 1926. Serial No. 123,536.

The present invention relates to an auxiliary air inlet and mixing device for motor vehicles and aims to provide a device of this nature whereby a gasoline motor automatically takes in auxiliary air for the purpose of thoroughly shattering all large particles of fuel supplied from the carburetor to the intake manifold of the engine, and converting said fuel into highly explosive car gas, thus preventing liquid fuel from passing into the cylinders to form carbon and dilute the crank case oil.

The advantages obtained from the device is that it sets up the efficiency of the motor whereby resulting in a smoother running motor, giving more power and speed without increasing the cost of operation.

This device is equipped with a specially designed ball valve which points directly upwardly. There are preferably a plurality of these valves for controlling them perfectly, and they do not move until the engine has acquired a certain speed that will remain closed while the motor is being started. When the motor starts, the suction of the cylinders lifts these balls and permits the air to be drawn in forcibly. It strikes the mixture as it is passing thru the intake manifold and successively shatters all large particles of fuel converting into a highly explosive dry gas which readily ignites.

Another important object of the invention is to provide a device of this nature which possesses an exceedingly simple construction that may be manufactured at a low cost, one which is thoroughly efficient and reliable in use, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:

Figure 1 is a side elevation of the device embodying the features of my invention, showing the same associated with the intake manifold of an engine.

Fig. 2 is a section taken substantially on the line 2-2 of Fig. 1, and

Fig. 3 is an elevation of another embodiment of the invention.

Referring to Figs. 1 and 2 of the drawing, 1 denotes a carburetor and 2 an outlet

pipe therefrom formed with a flange 3 at its free terminus. Intake manifold of the engine is indicated at 4 and which has that end opposing the free terminus of the outlet pipe 2, provided with a flange 5 of the same contour as the flange 3. Interposed between the flanges 3 and 5, as well as secured to said flanges by hold fast devices 6, only one of which is shown, is a vaporizing attachment in accordance with this invention, and which is referred to generally by the reference letter A.

The auxiliary air inlet and mixing device or attachment comprises a body portion 8 in the form of a plate of substantial thickness and which conforms in contour to the flanges 3 and 5. The body portion 8 gradually decreases in width from its transverse center toward each end, and each of its ends is slotted as at 9, for the passage of hold fast devices 6, these latter being arranged in each side of the pipe 2 and intake manifold 4. The hold fast devices 6 are provided with means for fixedly securing the body portion 8 between the flanges 3 and 5.

The body portion 8, centrally thereof, is provided with an opening 10 which registers with the openings formed respectively by the pipe 2 and intake manifold 4 and preferably the wall of the opening 10 acts as a continuation of the inner face of the pipe 2 and the intake manifold 4. The body 8 is formed on its lower edge with three cylindrical extensions having bores continued through the body 8 to communicate with the opening 10. These cylindrical extensions or nipples 12 are externally threaded for receiving caps 14 which are provided with relatively small air inlet openings 15 normally closed by ball valves 16.

The center nipple 12 has its axis and bore arranged vertically, and the axes and bores of the other two nipples are arranged obliquely thereto. Straight relatively short tube 17 has one end threadedly engaged in the bore of the central nipple 12 and tubes 18 are threadedly engaged with the other two bores of the nipples. The inner ends of the tubes 18 are curved inwardly toward each other to terminate in spaced relation. The tube 17 terminates below the space between the terminals of the tubes 18. The arrangement of these tubes 17 and 18 is an important feature of this invention, as it insures the effective and efficient breaking up of the particles of gas.

In Fig. 3, I have shown another embodiment of the invention wherein the intake manifold 4 is tapped by a pipe 19 communicating as at 20 with a straight tube 21 and a pair of curved tubes 22. Cylinders 23 are formed on the lower ends of the tubes 21 and 22 and have caps 14' associated therewith and similarly constructed with caps 14.

It is thought that the construction, operation, superior efficiency, of my invention, will now be clearly understood by those skilled in this art without a more detailed description thereof. The present embodiment of the invention has been disclosed in detail merely by way of example since in actual practice it attains the features of advantage enumerated as desirable in the statement of the invention and the above description. Numerous changes in the details of construction, and in the combination and arrangement of parts may be resorted to without departing from the spirit or scope

of the invention as hereinafter claimed or sacrificing any of its advantages.

Having thus described my invention, what I claim as new is:—

An auxiliary air inlet and mixing device comprising a plate having an opening adapted to communicate with the intake manifold of an engine and further provided with a plurality of atmospheric supply passages, three in number, communicating with said openings through the wall of the latter, valve controlled nipples extending from the exterior ends of said passages, tubes engaged in the interior ends of said passages and extending inwardly of the opening in a row, the outer tubes being bent inwardly towards each other to be disposed co-axially, the center tube extending between the outer tubes and terminating short of the axis of the co-axial alinement of the curved ends.

In testimony whereof I affix my signature.

YSABELLA D. McDONALD.
